Edward A. Henne

ATTORNEY.

UNITED STATES PATENT OFFICE.

HENRY C. NATERMAN, OF LOS ANGELES, CALIFORNIA.

DISPLAY HOLDER.

Application filed July 3, 1923. Serial No. 649,312.

To all whom it may concern:

Be it known that I, HENRY C. NATERMAN, a citizen of the United States, residing at Los Angeles, in the county of Los Angeles and State of California, have invented new and useful Improvements in Display Holders, of which the following is a specification.

This invention relates more specifically to a transparent cylindrical holder rotatively mounted for displaying and protecting printed matter, such as automobile licenses, telephone and other addresses that are constantly being used.

A main object of this invention is to provide a device that will securely hold in position and display a relatively long list of written or printed matter in a comparatively small space, which list may be readily removed therefrom and replaced by other lists as occasion demands.

A further object is to provide a display device that is simple in construction, easily operated, and that may be utilized in a number of different situations.

25 Further objects and advantages will be apparent from the following description, reference being had to the accompanying drawings, in which:

Fig. 1 is a side elevation of the display device attached to the steering column of an automobile.

Fig. 2 is a central vertical section through the holder.

Fig. 3 is a cross section taken on line 3-3 of Fig. 2.

Fig. 4 is a perspective view of the holder mounted in a desk frame.

Fig. 5 is an end view showing a means for preventing an accidental rotation of the holder.

Referring more particularly to the drawings, 6 designates the complete display holder, consisting of a cylindrical tube 7 preferably formed of glass, or other transparent material, having metal end caps, 8, 9, each provided with a centrally disposed aperture 10, 11, respectively. Display cylinder 7 is mounted between bearings 12, 13, formed by the upturned ends of a flat metallic supporting bar 14, the ends of the bearings being provided with bearing pins 15 formed of screws, the ends of which engage the apertures formed in the metal caps, thus permitting the tube 7 to freely rotate thereon. Rigidly secured to the bar 14

midway between its ends is a circular spring clamping member 16, the ends being provided with the usual securing bolt 17, by means of which it may be readily secured to a stationary support.

In Figs. 1 and 2 I have shown my device as adapted for holding an automobile license card 20. The printed card is rolled so that its diameter is less than the internal diameter of the transparent tube 7 into which it is inserted. When the license card or paper upon which it is printed, is released after insertion in the cylinder, the resiliency of the paper or card will cause the same to unroll and smoothly engage the inner surface 70 of the cylinder, as clearly shown in Fig. 3 of the drawings. The display device may be secured to the steering column 21 of an auto vehicle so that the license number and other matter on the license card may be 75 readily scrutinized by an authorized person when desired.

In Fig. 4 of the drawing, I have shown the device for use in connection with a desk, the clamp 16 being omitted from the supporting bar 14, and two cross bars 22, 23, being secured to said bar adjacent the ends thereof for supporting the device on the desk. When used in this manner a number of typewritten telephone addresses that are 80 most frequently used may be made on a slip of paper of the required size and inserted in the cylinder 7, slips containing new or corrected addresses may be substituted as occasion demands, the slips being readily removed from or inserted in the cylinder with 85 little or no inconvenience.

In Fig. 5 of the drawings, I have illustrated a modified form in which one of the end caps of the device is provided on its 90 periphery with a plurality of rounded notches 24, the ends of the spring finger 25, normally engaging the notches so as to prevent an accidental rotation of the cylinder 95 7 after it has been rotated to bring the desired information to the view of the operator.

From the above description it will be observed that I have provided a novel display device which may be conveniently utilized 100 in various situations, the rotating cylinder being capable of holding a typewritten list of addresses whose length will be approximately three times the diameter of the cylinder.

What I claim is:

1. A device of the class described, comprising a frame provided with aligned bearings, a transparent tube mounted in said bearings for rotation, and means mounted on said frame and engaging said cylinder to prevent an accidental rotation.
2. A device of the class described, comprising a frame provided with aligned bearings, a transparent tube having metal end

caps detachably secured thereto mounted in said bearings for rotation, one of said caps being provided with a serrated periphery, and a spring dog mounted on said frame and engaging the serrations on said cap to prevent accidental rotation.

In witness that I claim the foregoing I have hereunto subscribed my name this 4th day of June, 1923.

HENRY C. NATERMAN.
